CLAIM

I claim the ornamental design for a drain mat, as shown and described.

DESCRIPTION

FIG. 1 is a perspective view of a drain mat of the present invention.

FIG. 2 is a side elevation view taken from the lower left side of FIG. 1, the opposite side being identical.

FIG. 3 is an end elevation view taken from the lower right side of FIG. 1, the opposite end being identical.

FIG. 4 is a top plan view of the drain mat shown in the prior Figures; and,

FIG. 5 is a bottom plan view of the drain mat shown in the prior Figures.

1 Claim, 2 Drawing Sheets

FIG. 1

FIG. 2

FIG. 3

FIG. 4

FIG. 5
